UNITED STATES PATENT OFFICE

167,616

ICICLE HIGHBALL STIRRER AND COCKTAIL PICK

George Clare, Maplewood, N. J.

Application April 18, 1950, Serial No. 9,287

Term of patent 14 years

(Cl. D44—29)

To all whom it may concern:

Be it known that I, George Clare, a citizen of the United States of America and a resident of the city of Maplewood, in the county of Essex and State of New Jersey, have invented a new, original, and ornamental Design for Icicle Highball Stirrer and Cocktail Pick, of which the following is a specification, reference being had to the accompanying drawing, forming a part thereof.

Fig. 1 is a front elevational view of an icicle highball stirrer and cocktail pick, showing my new design;

Fig. 2 is a top view thereof; and

Fig. 3 is a bottom view thereof.

The dominant features of my design reside in the portions shown in full lines.

I claim:

The ornamental design for an icicle highball stirrer and cocktail pick, substantially as shown and described.

GEORGE CLARE.
